UNITED STATES PATENT OFFICE.

WILLIAM HAEHNEL, OF NEW YORK, N. Y., ASSIGNOR TO PALM & FICHTELER,
OF SAME PLACE.

DESIGN FOR ORNAMENTATION OF SEWING-MACHINES.

SPECIFICATION forming part of Design No. 14,958 dated April 15, 1884.

Application filed February 21, 1884. Term of patent 7 years.

To all whom it may concern:

Be it known that I, WILLIAM HAEHNEL, of New York, in the county and State of New York, have invented and produced a new and original Design for Ornamentation of Sewing-Machines, of which the following is a specification.

This invention relates to a new and original design for the ornamentation of sewing-machines and other articles; and it consists in the novel grouping and configuration of figures, hereinafter more fully described.

The accompanying illustrations show in Figures 1 and 2 opposite views of a sewing-machine plate and arm having thereon my new design. Figs. 3 and 4 are full-size detail views of the ornamentation at the sides of the cloth-plate. Fig. 5 is a full-size detail view of the ornamentation in the center of the cloth-plate. Figs. 6, 7, and 8 are full-size detail views of the ornamentation on both sides of the opening in the cloth-plate. Fig. 9 is a full-size detail view of the ornamentation at the front portion of the cloth-plate. Figs. 10 and 11 are full-size detail views of the ornamentation on both sides of the sewing-machine arm. Fig. 12 is a full-size detail view of the ornamentation on that side of the needle-carrying portion of the sewing-machine arm which is seen on Fig. 2. Fig. 13 is a full-size detail view of the ornamentation on the front of the sewing-machine arm. Fig. 14 is a full-size detail view of the ornamentation on that side of the needle-carrying portion of the sewing-machine arm which is seen on Fig. 1. Fig. 15 is a full-size detail view of the ornamentation of that side of the post which supports the sewing-machine arm which is shown in Fig. 1. Fig. 16 is a full-size detail view of the ornamentation of the front of the post supporting the sewing-machine arm. Figs. 17, 18, and 19 are full-size detail views of the ornamentations on that side of the post supporting the sewing-machine arm which is seen in Fig. 2.

The figures A A, which ornament the sides of the cloth-plate, consist of long curving tendrils alternately set with large and small pointed leaves and small buds, and bearing on their curved ends sets of star-flowers like small strawberry-blossoms.

Figure B, which ornaments the center of the cloth-plate, consists of two curved tendrils surrounding a set of star-flowers like small strawberry-blossoms, and having larger pointed leaves near the center, and smaller leaves and buds outside.

Figure C, which ornaments the side of the opening next to the center of the cloth-plate, consists of two sprays crossing each other, and bearing leaves and buds similar to those already described.

Figures D D, ornamenting the cloth-plate at the sides of the opening, consist of short curved sprays bearing leaves similar to those already described.

Figure E, ornamenting the front portion of the cloth-plate, consists of two long sprays crossing each other, each bearing on its curved end a set of star-flowers like small strawberry-blossoms.

Figures F F, ornamenting the sides of the sewing-machine arm, consist of sprays bearing larger and smaller leaves and star-flowers like small strawberry-blossoms, twined around the inscription "White," or other inscription, all placed against the side of the sewing-machine arm.

Figure G, ornamenting that side of the needle-carrying portion of the sewing-machine arm which is shown in Fig. 2, consists of a hook-shaped rod of the form shown, which has leaves similar to those already described.

Figure H, ornamenting the front of the needle-carrying portion of the sewing-machine arm, consists of a spray curved in such way as to describe the figure 8, and bearing larger and smaller pointed leaves, and also flowers and buds, similar to those above described, in its circles.

Figure I, ornamenting that side of the needle-carrying portion of the sewing machine arm which is shown in Fig. 1, consists of a curved spray bearing leaves and flowers similar to those above described.

Figure K, ornamenting that side of the post supporting the sewing-machine arm which is shown in Fig. 1, consists of a divided spray curved so as to form the figure S, bearing leaves and flowers similar to those above described.

Figure L, ornamenting the front of the post

supporting the sewing-machine arm, consists of a curved spray bearing leaves and flowers similar to those above described.

Figure M, ornamenting a part of the side 5 of the post supporting the sewing machine arm which is seen on Fig. 2, consists of two small curved sprays running alongside of each other and bearing leaves.

Figure O, ornamenting the same side of the 10 post below figure M, consists of a small curved tendril bearing small leaves and flowers similar to those heretofore described.

Figure P, ornamenting the same side of the 15 post below figure O, consists of a curved divided spray bearing flowers and leaves similar to those heretofore described.

I claim—

1. The design for the ornamentation of sewing-machines, consisting of the figure A, substantially as shown.

2. The design for the ornamentation of sewing-machines, consisting of the figure B, substantially as shown.

3. The design for the ornamentation of sewing-machines, consisting of the figure C, substantially as shown.

4. The design for the ornamentation of sewing-machines, consisting of the figure D, substantially as shown.

5. The design for the ornamentation of sewing-machines, consisting of the figure E, substantially as shown.

6. The design for the ornamentation of sewing-machines, consisting of the figure F, substantially as shown.

7. The design for the ornamentation of sewing-machines, consisting of the figure G, substantially as shown.

8. The design for the ornamentation of sewing-machines, consisting of the figure H, substantially as shown.

9. The design for the ornamentation of sewing-machines, consisting of the figure I, substantially as shown.

10. The design for the ornamentation of sewing-machines, consisting of the figure K, substantially as shown.

11. The design for the ornamentation of sewing-machines, consisting of the figure L, substantially as shown.

12. The design for the ornamentation of sewing-machines, consisting of the figure M, substantially as shown.

13. The design for the ornamentation of sewing-machines, consisting of the figure O, substantially as shown.

14. The design for the ornamentation of sewing-machines, consisting of the figure P, substantially as shown.

15. The design for the ornamentation of sewing-machines, consisting of the figures A, B, C, D, E, F, G, H, I, K, L, M, O, and P, substantially as shown.

WILLIAM HAEHNEL.

Witnesses:

GUSTAV SCHNEPPE,

JOHN M. SPEER.
